JOHN P. ROGERS, OF SAN DIEGO, CALIFORNIA

DEVICE FOR LAYING PLASTIC PAVEMENTS

Application filed October 22, 1929. Serial No. 401,454.

This invention relates to paving, and comprehends a device for forming an elastic joint in plastic pavements in order to compensate for the contraction and expansion thereof.

5 The invention comprehends a device for making provision when laying a plastic pavement, for a joint to allow for the contraction and expansion of the pavement in order to avoid cracking, which device consists of a 10 form member adapted to be installed over the surface to be paved in such a manner as to divide the plastic pavement forming material into independent areas, which form member is constructed in such a manner as to 15 facilitate its emplacement with respect to the pavement reinforcing means and to further facilitate its removal from between the adjacent formed pavement sections.

Other objects of the invention reside in 20 the simplicity of construction of the device employed, the economy with which the same may be produced and the general efficiency derived therefrom.

With the above recited and other objects 25 in view, reference is had to the following description and accompanying drawing, in which there are exhibited several examples or embodiments of the invention, while the claim defines the actual scope thereof.

30 In the drawing:

Figure 1 is a sectional perspective view illustrating the manner in which the device is employed during the laying of the pavement.

Figure 2 is a side view of the device or 35 form member.

Figure 3 is an enlarged transverse sectional view therethrough, taken approximately on the line 3—3 of Figure 2.

Figure 4 is a similar view of a slightly 40 modified form of the member.

Figure 5 is a side elevation of a still further modification of the invention.

Figure 6 is a sectional view illustrating the 45 last mentioned form installed in the pavement.

Referring to the drawing by characters of reference, the form member which constitutes an improved device for the laying of the pavement is in the nature of a strip 10 50 which is of greater width at its upper end

than at its lower end to provide upwardly diverging or downwardly converging sides 11, 11. In practice, the strip 10 is preferably constructed with a wooden core 12 which is covered by a sheet metal covering 13 extending around its side surfaces and lower edge with inturned flanges 14 partially overlying its upper edge. A heavier and more rigid length of sheet metal 15 overlies the upper edge of the core 12 and the flanges 14 and is preferably secured in place by screws or other fastening devices 16 which extend therethrough and are anchored into the core. The opposite ends of the upper covering sheet 15 extend beyond the ends of the core and the covering 13 and are bent inwardly and downwardly as at 17 to provide handle portions by virtue of which the strips may be handled.

The tapering form of the strip illustrated 70 in Figure 3 may be varied as illustrated in Figure 4, in which instance one of the side surfaces 18 is disposed at a right angle to the upper surface 19 and the opposite side surface 20 is inclined toward the lower edge 21 75 of the strip.

In use, the temporary form members 10 are positioned over the surface to be paved in such a manner as to subdivide the plastic or cementitious pavement forming material 22 into independent areas or blocks, as illustrated in Figure 1. In order, however, to avoid interference with the proper positioning of the strips described, the usual reinforcing material 23 is deflected or offset 80 downwardly as at 24 and the exposed bight portion will be protected at this point from moisture by tar paper 25.

In practice, the strips 10 will be positioned 90 over the surface to be paved in such a manner as to subdivide the plastic pavement forming material 22 into independent areas. The strips will remain in place for a sufficient length of time to allow the material to set or harden to such a degree as to permit of the removal of the form members or the strips 10 without defacing, damaging or otherwise marring the pavement surface. The strips or form members will then be removed and a suitable elastic or resilient filler will be in- 95 100

roduced into the spaces 26 formed between the adjacent pavement areas.

As an alternative to offsetting the reinforcing means 23, the strips or form members 10 as illustrated in Figures 5 and 6 of the drawing, may be provided with notches 27 extending upwardly from the lower edges to accommodate the reinforcing means 23 and to avoid the necessity of caking or offsetting the same. In use, the sides of the strips or form members 10 will be oiled or otherwise lubricated to facilitate their removal from between the adjacent paving sections or areas.

15 What is claimed is:

16 A form member for use in laying plastic pavements comprising an elongated substantially wedge shaped strip consisting of a wooden core, a sheet metal covering extending around the sides and lower narrow edge and a rigid metal strip of greater thickness than the covering arranged over the upper wider edge thereof, said latter strip extending beyond the ends of the core and bent 20 downwardly and inwardly to provide handles for facilitating the handling of the form member.
